UNITED STATES PATENT OFFICE.

ARTHUR HERMAN ADAMS, OF LA GRANGE, ILLINOIS, ASSIGNOR TO WESTERN ELECTRIC COMPANY, INCORPORATED, OF NEW YORK, N. Y., A CORPORATION OF NEW YORK.

STRAND-WORKING MACHINE.

Application filed May 30, 1924. Serial No. 716,846.

This invention relates to improvements in strand working machines, and more particularly to tension control mechanisms for such machines.

5 The primary object of the invention is to maintain uniform tension on a strand within a strand working apparatus by means controlled by the worked or completed strand.

10 The present invention is particularly designed for use in connection with strand working apparatus in which the working mechanism thereof tends to stretch the strand, the invention providing a means for reducing this stretching action and at all times maintaining uniform any stretching 15 of the strand that may occur. The invention is shown as applied to a mechanism for coating wire, but the invention may be 20 utilized for other purposes and is to be limited only by the spirit and scope of the appended claims.

In the accompanying drawing, which illustrates one embodiment of the invention,

25 Fig. 1 is a fragmentary side elevation showing the invention as applied to a strand coating apparatus, and

30 Fig. 2 is a front elevation of the mechanism shown in Fig. 1.

Referring now to the drawings in detail in which like reference numerals designate similar parts throughout the several views, 35 10 indicates generally a wire coating machine, schematically illustrated, of the type disclosed in Patent 1,303,070, granted Kochendorfer and Blount, May 6, 1919. This machine comprises essentially a framework 11 which carries what may be termed an oven 12 within which are disposed a plurality of vertical tubes 13 only one of which 40 is illustrated. These tubes are heated electrically by means (not shown) but which is fully illustrated in the patent above referred to.

45 The machine illustrated herein is particularly designed for applying and baking an insulating enamel coating upon wire. The enameling material is disposed within a receptacle 14 secured to the framework 50 11. Revolvably mounted within the receptacle 14 are a series of sheaves 15 mounted upon a stud shaft 16 secured to the side walls of the receptacle 14. The sheaves 15 are so disposed within the receptacle that

a portion of their surface is submerged with- 55 in the enamel in the container. Disposed above the oven 12 is a second series of sheaves 17 positioned in alignment with the sheaves 15 and rotatably mounted upon a shaft 18 carried by a suitable bracket 20 60 attached to any suitable support, such as an I beam 21 of the ceiling of the room wherein the apparatus is located. Also secured upon the I beam 21 or other suitable support is a bracket 23 which provides suitable bearings for a shaft 24 to which is secured a capstan 25. Also mounted upon the shaft 24 is a pulley 26 which may be driven by a belt 27 actuated by any suitable driving means (not shown). 70

The means for maintaining uniform any stretch on the wire treated by the machine comprises an arm 28 pivotally mounted upon a pin 29 carried by a bracket 30 secured to one side wall of the oven 12. Rotatably mounted adjacent to the free end of the arm 28 is a pulley 31 over which the coated wire is adapted to run, as will be hereinafter described. Attached to the arm 28 is a suitable friction brake 32 which is designed to contact with the head of a supply spool 33 rotatably mounted upon a horizontal stud 34 projecting from the wall of the oven 12. A tension spring 35 attached to one end to the arm 28 and its other end to the stud 34 tends normally to hold the brake 32 in contact with one head of the supply spool. 85

The operation of the apparatus is as follows: 90

The wire to be coated is fed from the supply spool 33 threaded around the first sheave 15 at the bottom of the machine then upwardly through the heating tube 13 and over one of the top sheaves 17, thence down the front part of the machine over the second sheave 15 at the bottom of the machine, this wire stringing operation through the heating tube and back down the front of the machine being continued for the number of 100 insulating coatings it is desired to bake upon the wire. After the wire has been strung through the heating tube for the last time it is carried over one of the sheaves 17 and is then looped around the pulley 31 carried by 105 the arm 28. From the pulley 31 the wire is looped about the capstan 25 which serves to feed it to a suitable take-up mechanism (not

- shown). As the machine operates, wire is drawn from the supply spool 33 through the compound in the container 14 and through the heating tube the desired number of times 5 by the capstan 25 after which it is fed to the take-up device (not shown). As the wire to be coated is pulled back and forth over the pulleys 15 and 17 by the capstan 25 it is stretched to some extent, and heretofore considerable difficulties have been encountered due to the fact that this stretching is not uniform and therefore results in a non-uniform product. These difficulties are overcome by the means herein disclosed, which 10 applies a braking effect to the supply spool in accordance with the tension on the coated wire whereby the final tension on the wire as it goes to capstan 25 is held substantially uniform. This is another way of saying that 15 the sum of all the frictional resistances or drags on the wire between the supply spool 33 and the capstan 25 is maintained substantially uniform. The operation of the brake 32 is readily apparent. When the tension on the wire looped about the pulley 31 exceeds a normal amount, the normal tension being set by the selection of a spring 35 having the proper tension, the arm 28 is 20 lifted disengaging the brake 32 from the supply spool 33 permitting this spool to revolve more freely, thereby reducing the total or final tension on the wire at capstan 25 to the normal amount. When, however, the tension on the wire falls below the normal 25 amount, the arm 28 is pulled downwardly by the spring 35 forcing the brake 32 into closer contact with the spool 33 retarding the rotation of the said spool and thereby increasing the tension on the wire between the supply spool and the capstan 25. Thus variations in the tension due to sheaves 15 and 17 or to the coating compound are instantly compensated for by varying the pressure on the supply spool brake 32. 30
- As previously stated, the tension controlling means is not limited for use with the type of machine disclosed but may be used in connection with any strand working apparatus without departing from the spirit and scope of the invention. 40
- What is claimed is:
1. The combination with a strand working apparatus having means for working the strand wherein the strand is looped back and forth a plurality of times and means for supplying strand to said working means, of means controlled by the worked strand for maintaining a uniform tension on the strand looped in said strand working apparatus. 45
  2. The combination with a strand working apparatus having means for working the strand wherein the strand is looped back and forth a plurality of times and rotatable means for supplying strand to said working means, of a brake for controlling the rotation of said rotatable supply and means controlled by the worked strand for controlling the braking effect of said brake. 50
- In witness whereof, I hereunto subscribe my name this 24th day of May A. D., 1924.

ARTHUR HERMAN ADAMS.
